UNITED STATES PATENT OFFICE.

HARRY C. KINSEL, OF ALTOONA, PENNSYLVANIA.

RAILWAY-SWITCH-THROWING MECHANISM.

1,098,809.

Specification of Letters Patent.

Patented June 2, 1914.

Application filed June 24, 1913. Serial No. 775,534.

To all whom it may concern:

Be it known that I, HARRY C. KINSEL, a citizen of the United States of America, residing at Altoona, in the county of Blair and State of Pennsylvania, have invented certain new and useful Improvements in Railway-Switch-Throwing Mechanisms, of which the following is a specification.

This invention relates to railway switch throwing mechanisms, and primarily contemplates improvements in the switch throwing devices as described in my former Patent No. 1,071,641, dated August 26, 1913, said improvements referring more particularly to the means for locking the switch point after the same has been set, by the magnet which controls its movement.

Another object of the invention is to provide means whereby the electrical devices are placed above the ground, thus eliminating, to a marked degree, the dangers arising from short circuits and burned magnet coils.

With these and many other objects in view which will be more readily apparent, as the nature of the invention is better understood, the same consists of the novel construction, combination, and arrangement of parts as will be hereinafter fully described, illustrated, and claimed.

It will be readily understood that this invention is quite susceptible to a wide range of structural modification without departing from the spirit or scope of the invention, but a preferred and thoroughly practical embodiment thereof is shown in the accompanying drawings, in which:

Figure 1 is a plan of the improved switch throwing device with the electrical connections and magnet housing. Fig. 2 shows a plan view of the magnet, and particularly illustrates the switch point locking feature. Fig. 3, shows a side view of the parts shown in Fig. 2. Fig. 4 shows a plan view of a track and switch point system, together with my improved switch throwing device applied thereto. Fig. 5 shows an end elevation of an electrical street railway car, together with the signal system and the manner of transmitting the electric current from the trolley wire to the switch throwing device. Fig. 6 shows the side elevation of the car shown in Fig. 5, and more particularly illustrates my method of taking the current

from the trolley wire through the trolley pole to the car. Fig. 7 illustrates the manner in which the trolley pole harp makes the electrical connection necessary to throw the switch point, shown in Fig. 4 of the drawings. Fig. 8 is a detail sectional view on the line A—B of Fig. 1.

Like reference numerals indicate similar parts throughout the several figures of the drawings.

The improved switch throwing mechanism may readily be used in connection with any type of railroad, whether steam or electric, but has preferably been shown in connection with a trolley road including the main track, designated by the numeral 10, the siding or branch line 11, and the switch point 12 at the junction 13 of the main and branch lines.

The switch throwing mechanism, designated in its entirety by the numeral 14, is preferably positioned in a casing 15, having a lid 16, together with means 17 for securing the lid to the casing, for the purpose of excluding moisture, etc. This improved switch point throwing mechanism consists primarily of a magnet 18, a stem 19, a switch point bar 20, and means for actuating the bar. The stem 19 is preferably constructed with a rectangular portion 23, held in alignment with the central portion of the magnet 18 by a plurality of supporting columns 24 and 25. The rectangular portion 23 of the stem 19 is provided with a T head 26, which is firmly secured to the stem 19 by a plurality of machine screws 27. The arms of the T head 26 are each provided with a substantial dowel or locking pin 29, which is designed to enter a corresponding keeper opening 30 in the upstanding arm 31, attached to the switch point rod 32. The function of this device is to insure that the switch is either locked in its open, or in its closed position.

The operation of the switch, by the magnet, is the same for this device as that which is described in the specification of my former Patent No. 1,071,641, dated August 26, 1913, but in order to make the new switch point locking feature clear, the operation, in brief, may be described as follows: Electric current enters the magnet coil through the wire 33, energizes the magnet and returns

on the wire 34 to the ground. When the magnet is energized, the stem 19 is pulled into the magnet bore 35, with a very rapid movement. The rectangular portion 23 of 5 the said stem is provided with a pendent swinging arm 36, which is fulcrumed at the point 37, said arm being further provided with a friction roller 38, designed to operate on a cam 39 of the disk 40. The said disk 40 10 is provided with peripheral teeth 41, which engage the rack 42 on the switch point throwing rod 32. In connection with this rod 32 it will be observed that the same is provided with an angularly disposed arm 15 132 carrying an offset conductor finger 133 which is connected in the conventional manner to the main current line M, and suitably insulated from the arm 132 as indicated at 134. The said conductor finger 133 being 20 carried by the arm 132 which is secured to the rod 32, is adapted to move in the recessed portion of an insulated bracket 135, when the said rod 32 is actuated as previously described. In the bottom of the recess in the 25 insulated bracket 135 is a contact plate 136 which is suitably connected to the wire 51 which leads to the red light R upon the signal pole 47. Thus, it will be apparent that when the rod 32 has been properly pulled 30 over so that the current is established between the main current line M and either the wire 49 leading to the white light, or the wire 50 leading to the green light, that the conductor finger 133 will be resting on an 35 insulated portion of the insulated bracket 135 so that no current can get to the contact plate 136 and thereby light the red light. However, should the magnet 18 fail to pull the rod 32 so that current is sent through the 40 proper means to the white W or green light G, the contact finger 133 will be left in the middle of the recess of the bracket 135 and resting on the contact plate 136 thereby sending the current from the main line M 45 through the wire 51 to the red light R, indicating that the switch is in a dangerous position. The coiled spring 43, which abuts against the upstanding magnet stem support and continually exerts a force against the 50 top of the T head, in conjunction with the inclined face 44 of the cam, insures that the magnet by exerting a pulling effort in the stem will either lock or unlock the switch. The arm 36 is provided with a tail piece 45, 55 which carries a carbon 46, and when thrown—as shown in Fig. 1 of the drawings—shows the motorman that the track is not clear and the movement is to be made with caution, and if thrown in the opposite direction 60 would indicate that the track was clear and to proceed with the authorized speed; but, if, for instance, the switch point was locked in its mid-position and neither the white or

green lamp, showing on the signal pole 47, the red lamp would appear lighted since the 65 lamp current would come in on the same wire, but instead of going out on wires 49 or 50 to the white or green lamp, it would be transmitted through the wire 51 and thence to the red lamp, thus indicating that there 70 was something wrong with the switch point, as previously described.

The current for operating the magnet 18 is preferably taken from the trolley wire, a diagrammatic outline of the circuits being 75 shown in Figs. 5 and 7 of the drawings.

The trolley harp 52 is preferably provided with means for transmitting the electric current from the trolley wire through wire 53, to a snap switch S, shown diagrammatically 80 in Figs. 5 and 6, located inside the car for controlling the magnet which operates the switch points 12 and 13. This can readily be accomplished since the circuit through the magnet can be completed by turning the 85 snap switch, thus allowing the current from the trolley wire to pass down wire 53, thence through the snap switch and through wires 54 to the magnet, and then grounding through wire 55, which is attached to one of 90 the main rails 56. It will be further noted that the inclined faces 44 of the cam converge at the point 44^a: this construction making a self-adjusting means for the friction roller 38, making it impossible for the 95 roller to stop in such a position as to be unable to move the switch when the magnet is energized.

From the foregoing it is thought that the many advantages of the herein described 100 switch point throwing device will be readily apparent without further elaboration, and

What I claim as new and desire to be secured by Letters Patent is:

1. An electric switch throwing device 105 including, in combination with the switch point, a rack operatively connected with the switch point, a toothed member engaging the rack, and a magnet controlled stem operatively engaged with said toothed member 110 for oscillating the same and also carrying locking means coöperating with the rack.

2. An electric switch throwing device including, in combination with the switch point, a rack operatively connected with the 115 switch point and provided with keepers, a toothed disk engaging said rack, and a magnet controlled reciprocating stem having an operative engagement with the disk for oscillating the same and also provided with 120 locking dowels adapted to engage said keepers.

3. A switch operating device including a base, a solenoid magnet having a reciprocating stem, a toothed disk rotatable on the 125 base, a link connection between the stem of

the magnet and the disk, a rack slideable over the base and in mesh with the disk, a locking device comprising keepers on the rack and dowels on the stem, switch point engaging means carried by the rack, and a circuit including a manually operated switch on the car for energizing the magnet.

In testimony whereof I hereunto affix my signature in the presence of two witnesses.

HARRY C. KINSEL.
